SOOT BLOWER

Norman L. Snow, New Canaan, Conn., and Willis P. Thomas, Highland Park, Harry E. Brelsford, Birmingham, and Curtis L. Howse and Frank Bowers, Detroit, Mich., assignors to Diamond Power Specialty Corporation, Detroit, Mich., a corporation of Michigan

Application December 27, 1932, Serial No. 649,106

23 Claims. (Cl. 122—392)

This invention relates to a fluid heater cleaner of the character in which a blower element is arranged to discharge cleaning fluid adjacent portions of a fluid heater to be cleaned.

One of the primary objects of this invention is to provide a fluid heater cleaner of the above mentioned character which will include means for initiating the operation of the cleaner and means for terminating the actuation of the cleaner after a predetermined desired operation thereof.

The invention further contemplates the provision of means whereby the extent of operation of the cleaner may be varied at the will of the operator to the end that the cleaner may be caused to operate for short or long periods of time as desired.

The above and numerous other objects and advantages of this invention will become more apparent as the following description proceeds, particularly when reference is had to the accompanying drawings, wherein:

Fig. 1 is a longitudinal sectional view through a blower head constructed in accordance with the teachings of this invention;

Fig. 2 is a sectional view taken substantially on the line 2—2 of Fig. 1;

Fig. 3 is a fragmentary sectional view taken substantially on the line 3—3 of Fig. 1;

Fig. 4 is a fragmentary sectional view similar to Fig. 1 showing a slightly modified form of construction;

Fig. 5 is a view similar to Fig. 4 showing the parts of the construction in one of the positions which they assume during a portion of the operation of the construction;

Fig. 6 is a sectional view taken substantially on the line 6—6 of Fig. 5;

Fig. 7 is a perspective view with parts broken away of a slightly modified form of control mechanism;

Fig. 8 is a longitudinal sectional view through a portion of the structure shown in Fig. 7;

Fig. 9 is an enlarged sectional view through a portion of the structure shown in Fig. 8;

Fig. 10 is an end elevational view partly in section of a further modified form of construction;

Fig. 11 is a sectional view taken substantially on the line 11—11 of Fig. 10;

Fig. 12 is a view similar to Fig. 10 showing a further modified form of construction;

Fig. 13 is a side elevational view of a portion of the structure shown in Fig. 12;

Fig. 14 is a fragmentary sectional view taken substantially on the line 14—14 of Fig. 12;

Fig. 15 is a detail perspective view of one of the elements forming a part of the structure shown in Fig. 12;

Fig. 16 is a diagrammatic view of a fluid heater showing a plurality of cleaners associated with the same and a modified means for controlling these cleaners;

Fig. 17 is a fragmentary and elevational view of the structure shown in Fig. 16;

Fig. 18 is a perspective view of a central control means for a plurality of blowers;

Fig. 19 is a semi-diagrammatic sectional view showing a further modified form of control means;

Fig. 20 is a sectional view taken substantially on the line 20—20 of Fig. 19;

Fig. 21 is a view similar to Fig. 19 showing a further embodiment of the control mechanism;

Fig. 22 is a view similar to Fig. 19 showing a further modified form of the invention;

Fig. 23 is a sectional view through a portion of the structure shown in Fig. 22;

Fig. 24 is a view similar to Fig. 19 showing a further embodiment of the inventive idea;

Fig. 25 is an enlarged elevational view of a portion of the structure shown in Fig. 24; and

Fig. 26 is a detail end elevational view of the structure shown in Fig. 25.

Referring then particularly to the drawings wherein like reference characters designate corresponding parts throughout all views, there is shown in Fig. 1 a blower element 25 which, it will be understood, extends into a fluid heater (not shown) and is provided with a suitable nozzle or nozzles (not shown) for discharging cleaning fluid adjacent the portions of the fluid heater to be cleaned. The blower element is journaled in a head designated generally by the reference character 26, this head including means for rotating or oscillating the blower element, means for controlling the admission of cleaning fluid to the blower element, and means for controlling the extent of operation of the blower element, as will hereinafter be more fully described.

The head comprises a housing 27 which may be suitably mounted, if desired, on the wall of the fluid heater cleaner in any desired manner (not shown). A cover 28 closes one side of the housing 27, and this cover carries a bushing 29 which provides a bearing for the end of the blower element 25. The cover plate also receives one end of a sealing bushing 30 which is carried in a valve housing designated generally by the refer-

ence character 31. This valve housing provides a cleaning fluid inlet passage 32 to which a source of supply of cleaning fluid may be connected in any desired manner.

5 The mechanism for rotating the blower element comprises a gear 35 fixed as by a set screw or the like 36 to the blower element. Engaging this gear is a pinion 37 which is journaled on a shaft 38 mounted in the housing 27. Mounted 10 on the hub of pinion 37 and fixed thereto is a ratchet wheel 39 so that upon rotation of this ratchet wheel the pinion 37 is rotated, thus driving the gear 35 and blower element 25.

Formed in caps secured to the housing 27 are 15 cylinders 40 and 41. These cylinders are aligned, and mounted in the same are pistons 42 and 43, these pistons being connected by a yoke 44. The yoke is provided with a slot 45 through which the shaft 38 extends, so that the pistons may reciprocate in their respective cylinders and impart reciprocal movement to the yoke.

20 Pivotal secured to the yoke 44 are pawls 46 and 47, and springs associated with these pawls constantly urge the same into engagement with 25 the ratchet wheel 39. The pawl 46 is mounted above the longitudinal axis of the yoke 44, while the pawl 47 is mounted below the longitudinal axis of this yoke. The arrangement is such that as the yoke is moved to the left, as viewed in 30 Fig. 2 of the drawings, counter-clockwise movement is imparted to ratchet wheel 39 by pawl 46, the pawl 47 idling over the teeth of the ratchet wheel during this movement. Upon reverse movement of the yoke or movement thereof toward the right, as viewed in Fig. 2, pawl 47 imparts counter-clockwise movement to the ratchet wheel 39, pawl 46 idling over the teeth of the ratchet wheel during this movement of the yoke. Thus it will be apparent that reciprocation of 40 the pistons 42 and 43 and thus of the yoke drives the ratchet wheel 39 continuously in one direction and thus the blower element 25.

For admitting fluid under pressure to the cylinders 40 and 41 to thus effect a reciprocation of 45 the pistons in these cylinders, there is provided a valve 50 mounted for reciprocation in a valve chamber 51 formed in the lower end of the housing 27. The valve member comprises an elongated tubular member providing a central passage 52. 50 The valve member is provided on its outer periphery and adjacent its ends with the relatively wide annular channels 53 and 54.

Fluid under pressure is supplied to chamber 51 by a conduit 55, this conduit discharging the 55 fluid into one end of the chamber. When the valve is in the position shown in Fig. 3 of the drawings, fluid under pressure may pass from conduit 55 by way of channel 53 into a passage 56 which communicates with the end of cylinder 41. At the same time channel 54 places 60 passage 57 which communicates with the end of cylinder 40 in communication with the interior of housing 27 by way of a passage 58 formed in the housing adjacent the valve chamber 51 therein. Thus it will be apparent that in the 65 position of the parts shown in the drawings, the cylinders have completed their movement in one direction and the valve has been shifted so that the pistons are about to start their movement in the other direction.

70 It will be understood that when the valve 50 is shifted to the right, as viewed in Fig. 3 of the drawings, the cylinder 41 will be connected to the exhaust, while cylinder 40 will be connected to the source of fluid under pressure. Such a posi-

tion of the valve is shown in dotted lines in Fig. 3, and by reference to this dotted showing it will be noted that fluid under pressure may pass from the left hand end of chamber 51 to the right hand end thereof by way of passage 52. From the right hand end of the chamber the fluid under pressure may enter channel 54 by way of the bypass formed by bore 59, and from the channel 54 the fluid under pressure may of course enter the cylinder 40 by way of passage 57. At this time cylinder 41 will be connected to the exhaust by way of channel 53 which places the passage 56 in communication with passage 60 which opens to the interior of the housing 27.

For actuating the valve, there is provided an 1 arm 61 which is fixed to the valve and which has a bifurcated end 62 which embraces a rod 63 carried by lugs 64 which depend from the yoke 44. Springs 65 and 66 are mounted on the rod 63 between the lugs 64 and the arm 61, with the 2 result that these springs act on the arm 61 to urge the same in one direction or the other.

It is of course desirable that the movement of the valve be substantially instantaneous as the pistons approach the limits of their movement in one direction or the other. For this purpose locking means is provided for restraining the valve against movement until the pistons have substantially completed their strokes. This locking means comprises levers 70 pivotally 3 mounted within housing 27 on opposite sides of arm 61. The levers 70 have arms 71 connected by a spring 72 which functions to normally urge the levers about their pivots or into engagement with the arm 61. A pin 73 fixed to the yoke 44 3 is arranged to alternately engage the arms 71 to thus alternately move the levers to their releasing positions.

Each lever is provided on its under face with shoulders 74 and 75 adapted to engage the sides 4 of arm 61. These shoulders limit movement of the arm as will now be described.

With reference to Fig. 2 of the drawings, it will be noted that the valve 50 has been moved to a position adjacent the right hand end of chamber 51. When the valve is in this position the shoulder 75 on the lever to the right of the arm 61 is in engagement with this arm to thus limit further movement of the valve to the right. The shoulder 74 on the lever on the left hand side of the arm, as viewed in Fig. 2, is engaging the arm to hold the valve against movement to the left. At this time fluid is being admitted to cylinder 41 while cylinder 40 has been opened to the exhaust, with the result that the pistons and the yoke are about to move to the left. As the yoke moves to the left it will be apparent that spring 65 will be compressed by the arm 61 and lug 64. The valve, however, will not be moved to the left until pin 73 strikes the arm associated with the lever to the left of arm 61. At this instant this lever will be raised to release the engagement of its shoulder 74 with the edge of arm 61, with the result that at this instant spring 65 will act to move the arm 61 and the valve to the left until the arm engages the shoulder 75 formed on the lever at the left side of the arm. Thus it will be apparent that as the yoke is reciprocated the valve 50 will be periodically actuated to alternately place the cylinders in communication with a source of fluid under pressure and with an exhaust. By properly locating the pin 73, cushioning of the pistons at either or both ends of their strokes may be effected.

As brought out before, fluid under pressure 7

is supplied to the valve chamber by way of conduit 55, and this conduit has its inlet end tapped into a chamber 76 formed in the valve housing 31. A passage 77 provides communication between chamber 76 and passage 32, and a valve 78 is provided for normally closing this passage, there being provided a spring 79 for holding the valve 78 in its closed position. Formed in the valve housing adjacent chamber 76 is a second chamber 80 which communicates with the interior of the blower element by way of a passage 81. A valve seat 82 is disposed between chambers 76 and 80, and the valve 78 cooperates with this valve seat to close communication between chambers 76 and 80 when the valve 78 has been shifted to the left, as viewed in Fig. 1 of the drawings, to place passage 32 in communication with chamber 76.

For actuating the valve 78, there is provided a stem 83 normally held in valve-releasing position by a spring 84. A lever 85 pivotally secured to the end of the valve casing 31 has a cam face 86 adapted to engage the end of the stem 83 when this lever is actuated by a depending actuating chain 87.

For controlling the admission of cleaning fluid to the blower element, there is provided a valve 90 mounted in the valve casing 31. The stem 91 of this valve is secured to a piston 92 mounted for reciprocation in a cylinder 93. A spring 94 disposed in this cylinder operates to close the valve 90 when the fluid pressure, which builds up back of the piston by virtue of the leakage of the cleaning fluid around the same, balances the fluid pressure acting on the front face of the piston. Whenever chamber 93 is opened to the exhaust, as will hereinafter be described, the pressure of the cleaning fluid in passage 32 acting on the forward face of piston 92 moves this piston to the right, as viewed in Fig. 1, to thus open valve 90 and admit cleaning fluid to the blower element.

For periodically placing cylinder 93 in communication with the exhaust as the blower element is rotated, there is provided a cam 95 fixed to the gear 35 for rotation with the same. This cam is arranged to engage a lever 96 pivotally secured to the housing 27, and this lever has a cam face 97 arranged to engage a valve 98. This valve when actuated by lever 96 places chamber 99 in communication with the atmosphere by way of passages 100. A conduit 101 provides communication between chamber 99 and cylinder 93, with the result that when valve 98 is actuated, cylinder 93 is placed in communication with the atmosphere, and thus valve 90 is opened. A spring 102 closes valve 98 when the lever 96 drops out of engagement with this valve.

In use, operation of this form of construction may be initiated by pulling downwardly on chain 87. This causes stem 83 to move valve 78 to the left, thus placing passage 32 in communication with chamber 76. The pressure of the cleaning fluid in passage 32 acting on the valve 78 will hold the valve in this position against the force exerted by spring 79.

Fluid under pressure from chamber 76 will be supplied to valve chamber 51 by way of conduit 55 so that the pistons 42 and 43 will start to reciprocate. Reciprocation of these pistons will effect a rotation of ratchet wheel 39 which, by way of pinion 37 and gear 35, will rotate the blower element. As brought out before, upon reciprocation of the pistons and of the yoke, the valve 50 will be periodically actuated to alter-

nately place the cylinders 40 and 41 in communication with the source of fluid supply and the exhaust.

As the blower element rotates, the cam 95 will be moved to actuate lever 96 and to thus exhaust the fluid under pressure from cylinder 93. At this time the pressure of the cleaning fluid acting on the face of piston 92 will move this piston to open valve 90 to thus admit cleaning fluid under pressure to the blower element, it being understood that at this time the cleaning fluid will be discharged from the blower element adjacent the portions of the fluid heater to be cleaned.

As soon as cleaning fluid under pressure is admitted to the blower element, this cleaning fluid enters chamber 80 by way of passage 81. The pressure of the cleaning fluid in chamber 80 acting on valve 78 moves this valve to the right, thus closing communication between chamber 76 and passage 32. When the valve is in this position, however, fluid under pressure may flow from chamber 80 to chamber 76 through valve seat 82, so that fluid under pressure will continue to be supplied to the valve chamber 51 from the blower element by way of passage 81, chamber 80, etc.

Thus the pistons will continue to reciprocate and the blower element will continue to rotate until the cam 95 passes out of engagement with lever 96. At this instant the valve 98 will close, thus closing communication between cylinder 93 and the exhaust. The cleaning fluid then leaking around piston 92 will build up a pressure in cylinder 93, with the result that the valve 90 will be moved to its closed position.

The closing of valve 90 will of course cut off the admission of cleaning fluid to the blower element, with the result that cleaning fluid will no longer be supplied to the valve chamber 51. This will result in a termination of the reciprocation of the pistons 42 and 43 and in a termination of the rotation of the blower element. It will thus be apparent that once the operation of the blower element is initiated by pulling on the chain 87, the blower element will rotate through one revolution, during which time cleaning fluid will be admitted to the blower element during a portion of its movement. When the movement of the blower element is terminated, the valve admitting cleaning fluid to the same will be closed, and the parts will be in position for the next cleaning operation.

In Figs. 4 to 6, inclusive, a slightly modified form of control device is shown, this device being adapted to be added to the structure above described to vary the number of rotations of the blower element incident to each operation thereof. Referring then particularly to these figures of the drawings, it will be noted that there is fixed to the valve casing 31^a a housing 105, this housing having a depending portion 106 bored to receive a plunger 107. The actuating chain 87^a is connected to the lower end of plunger 107 so as to be adapted to move the same downwardly against the tension of spring 108. The plunger is provided with a tapered portion 109 intermediate its ends, this tapered portion constituting a cam for moving the stem 83^a to the left when the plunger is pulled downwardly.

Mounted in suitable guides 110 in housing 105 is a member 111. This member is adapted for sliding movement longitudinally of the guides 110 and is normally urged to the left, as viewed in Fig. 4, by a spring 112 which engages a block 75

113 which depends from the member 111. The block 113 is provided with stepped shoulders 114 adapted for engagement with the upper end of plunger 107.

5 The member 111 carries on its upper face a block 115 having ratchet teeth 116 adapted to be engaged by a pawl 117 secured to the end of a stem 118 which is fixed to the piston 92^a for reciprocation with the same. Guides 119 formed 10 on the side of housing 105 tend to hold the pawl 117 out of engagement with ratchet teeth 116 during a portion of the longitudinal travel of stem 118. Formed in the opposite sides of the housing are openings 120 into any aligned pair 15 of which a pin 121 may be inserted, this pin limiting forward movement of member 111 by engaging the forward end of block 115.

In the operation of this form of construction, the number of rotative movements to be imparted 20 to the blower element may be determined by inserting pin 121 in the proper pair of holes 120. Thus, if it is desired that the blower element rotate four times, the pin would be inserted in the 25 fourth hole from the right, as indicated in Fig. 5 of the drawings. With the pin inserted in this hole, a downward pull on chain 81^a would cause plunger 107 to move stem 83^a to the left, thus opening valve 78^a to admit fluid under pressure to the control valve (not shown) for the actuating pistons. Obviously, this downward pull 30 of the plunger would move the upper end thereof out of the path of travel of the member 111, thus permitting this member to move to the left to the position shown in Fig. 5 of the drawings.

35 The blower element would be rotated by admission of fluid under pressure to the actuating pistons, and once during each revolution of the blower element the valve 90^a would be actuated as previously described. Each time the valve 40 90^a is opened, it would act through stem 118, pawl 117 and ratchet teeth 116 to move member 111 one step to the right, so that the upper end of plunger 107 would engage the next higher step 114. Since the plunger 107 will be held downwardly by the portion 113 of the member 111 until the member 111 is moved entirely to the right or to the position shown in Fig. 4 of the drawings, it will be apparent that the valve 78^a 45 will be held open until the blower element rotates a sufficient number of times to effect this movement of the member 111. Obviously, when the member 111 has been moved sufficiently far to the right so that the upper end thereof clears the top plunger 107, thus permitting the plunger 50 55 to return to its original position, the valve 78^a will then close communication between passage 32^a and chamber 76^a. The blower element will then continue to rotate until valve 90^a cuts off the admission of cleaning fluid to the blower element, at which time rotation of the blower element will be stopped.

From the above it will be apparent that the attachment disclosed in Figs. 4 to 6, inclusive, may or may not be added to the head disclosed in 60 Figs. 1 to 4, inclusive. When this attachment forms a part of the control mechanism, the blower element may be caused to operate a desired number of times by properly locating pin 121 in housing 105.

70 In Figs. 7, 8, and 9 a modified form of construction is disclosed in which, as in the last described form of construction, the number of rotative movements and thus the number of operations of the blower element may be regulated 75 as desired. In this embodiment of the invention,

the blower element 25^b is shown as being journaled in a head designated generally by the reference character 26^b. This head comprises a gooseneck 125 in one end of which the blower element is journaled and to the other end of which 5 cleaning fluid is supplied by a suitable supply pipe 126. A gear 35^b is fixed to the blower element for rotating the same, and this gear is driven by a pinion 127 which is mounted on the driven shaft 128 of a suitable fluid motor which 10 may be of any desired character and which is designated by the reference character 129.

Cleaning fluid is periodically admitted to the blower element upon rotation thereof by mechanism which includes a cam 95^b fixed for rotation with the gear 35^b, this cam engaging a suitable trigger 130, this trigger in turn engaging the stem 131 of a valve 132. Periodically upon rotation of the blower element the stem 131 is depressed to open the valve 132 to thus admit 20 cleaning fluid from the supply pipe to the blower element. A leaf spring 133 connected to the valve stem aids in closing the valve.

25 Mounted in the supply pipe 126 in advance of the valve 132 is a valve 135. Tapped into the head 26^b but between valves 135 and 132 is a conduit 136 which supplies cleaning fluid under pressure to the fluid motor 129, the exhaust from this motor being conducted to any suitable point by a conduit 137. The arrangement as 30 thus far described is such that when the valve 135 is opened, fluid under pressure will be immediately admitted to the fluid motor to rotate the latter. Cleaning fluid, however, will only be admitted to the blower element periodically as 35 the valve 132 is opened during rotation of the blower element.

Connected to the valve 135 is a stem 138, and this stem is secured to a piston 139 which is mounted for reciprocation in a cylinder 140. 40 This cylinder is in communication with the supply pipe 126 so that fluid in the supply pipe may leak around the piston to build up a pressure in back of the same, the arrangement being such that when the pressure of the cleaning fluid in 45 back of piston 139 balances the pressure of the cleaning fluid acting on the front face of the piston, the force of spring 141 will move the valve 135 to closed position. Obviously, whenever the space in cylinder 140 between the piston 139 and 50 the closed end of the cylinder is opened to the exhaust, the cleaning fluid acting on the face of piston 139 will move this piston to thus move the valve to its open position.

For controlling communication between the 55 cylinder 140 and the atmosphere and to thus provide means for exhausting the fluid pressure from in back of piston 139, there is provided a conduit 145. Mounted in this conduit is a valve 146 normally held closed by a spring 147. When the 60 valve 146 is opened against the force exerted by the spring, fluid under pressure from cylinder 140 may be exhausted by way of the discharge end 148 of the conduit 145.

For actuating the stem 150 of valve 146, there 65 is provided a cam 151, and this cam is fixed to a sleeve 152 which is rotatably journaled on a shaft 153. Fixed to the sleeve 152 for rotation with the same is a ratchet wheel 154, and suitably supported from the head 26^b is a lever 155 which 70 carries a pawl 156, this pawl engaging the ratchet wheel 154 to rotate the latter. The pawl engages the ratchet wheel tangentially and the teeth of the latter are preferably so arranged that each rocking of the lever 155 moves the ratchet wheel 75

one tooth. Chains 157 and 158 secured to the opposite ends of the lever 155 provide means for actuating this lever.

The sleeve 152 is frictionally constrained to rotate with the shaft 153 by a ball 159 mounted in a suitable bore formed in a boss 160 in the sleeve 152. A spring 161 adjustable by a threaded plug 162 engages the ball 159 to urge the same into engagement with recesses 163 spaced circumferentially of the shaft 153.

Fixed for rotation with the blower element is a pinion 165, and this pinion drivingly engages a gear 166 fixed to the shaft 153. The arrangement is such that when the blower element is rotated, the gear 166 and thus the shaft 153 will be rotated.

In the operation of this form of construction, when the valves 132 and 135 are closed, the blower element will be at rest, no cleaning fluid 20 at this time being supplied to the same. It will be understood that at this time the cutaway portion of the cam 151 will be opposite the valve stem 150 so that the valve 146 will be closed.

If now, it is desired to effect an operation of 25 the blower element, the lever 155 will be rocked by a proper pulling on chains 157 and 158, this rocking of lever 155 effecting a rotation of the ratchet wheel 154 in the direction of the arrow in Fig. 7 of the drawings. The shaft 153 will be held 30 stationary during this actuation of the ratchet wheel by virtue of the inertia of and the resistance to rotation of the gear 166, blower element 25b and associated structure. Thus, upon rotation of ratchet wheel 154 by pawl 156, this ratchet 35 wheel and the cam will be rotated with reference to the shaft 153, the cam engaging stem 150 to open valve 146.

Opening of valve 146 permits fluid to exhaust 40 from the closed end of cylinder 140 whereupon the pressure of the cleaning fluid acting on the 45 face of piston 139 moves this piston to cause the same to open valve 135. Upon opening of valve 135 cleaning fluid passes immediately to the fluid motor 129 by way of conduit 136, thus 50 causing this fluid motor to rotate pinion 127 and the blower element 25b. As the blower element rotates, the valve 132 will be periodically opened to admit cleaning fluid to the blower element during a predetermined portion of the rotation 55 thereof.

It will be apparent that as the blower element rotates, the gear 166 will be rotated, thus 60 rotating shaft 153. The sleeve 152 being frictionally constrained to rotate with shaft 153 by 65 spring-pressed ball 159, will thus be rotated to move the cam 151 to its original position where its cutaway portion again registers with the valve stem 150, thus permitting valve 146 to close. Obviously, as soon as valve 146 closes, pressure will 70 build up in back of piston 139, thus effecting a closing of main valve 135 and a termination of the operation of the fluid motor 129 and of the blower element.

The several gears and associated parts are 75 preferably so designed that a single pull on chain 158 ratchets the ratchet wheel 154 around one tooth, and moves the cam 151 sufficiently that the cutaway portion of this cam will be brought into registration with the valve stem 150 after the blower element has made one revolution. If it is desired that the blower element make two or more revolutions, two or more pulls are imparted to the chain 158, thus causing the cutaway portion of the cam 151 to be moved farther away 80 from the valve stem 150. Obviously, the number

of pulls imparted to the chain 158 determines the movement of the cam 151 with reference to the valve stem and thus predetermines the amount of reverse movement of the cam necessary to permit a closing of valve 146 and a termination of 85 the operation of the blower element.

It is to be understood that the fluid motor 129 may be adapted to drive the blower element either continuously in one direction or to oscillate the blower element. If the blower element is rotated continuously in one direction, the valve 132 10 will be utilized to limit the supply of cleaning fluid to the blower element to a portion only of its rotative movement. If, on the other hand, the blower element is oscillated by the motor 129, the 15 valve 132 may be eliminated since the blower element will be oscillated only through the arc in which blowing is desired.

In Figs. 10 and 11 a further modified form of construction is disclosed as comprising a blower 20 element 25c which is suitably journaled in a head designated generally by the reference character 26c. The head in this instance may be similar to the head shown in Fig. 7 of the drawings, thus including a gooseneck 125c through which cleaning 25 fluid is supplied to the blower element. A supply pipe 126c supplies cleaning fluid to the gooseneck, there being provided a valve 132c which controls the flow of cleaning fluid from the supply pipe to the gooseneck. The stem 30 131c of this valve is adapted to be actuated by a lever 130c which in turn is actuated by cam 95c upon rotation of the blower element, with the result that each time the blower element is rotated the valve is opened for a portion of the 35 rotative movement.

For rotating the blower element or, if desired, oscillating the same, there is provided a fluid motor 129c which in this instance drives a worm 175 which engages a worm wheel 176 fixed 40 to the blower element. Fluid under pressure is supplied to the fluid motor by way of conduit 136c which, it will be noted, may be conveniently tapped into the supply pipe 126c. An exhaust conduit 137c is provided for the fluid motor, this 45 exhaust conduit being arranged to discharge at any desired point remote from the fluid motor.

For controlling the flow of fluid under pressure through conduit 136c and thus to control 50 the actuation of motor 129c and the operation 55 of the blower element, there is provided a valve 177. This valve is provided with a stem 178 and is normally held in closed position by a spring 179 which surrounds the valve stem and engages a collar on the same.

Suitably journaled in a support 180 carried by the blower head is a shaft 181, and secured to this shaft for rotation with the same is a ratchet wheel 182 and a cam 183. The cam is so positioned as to engage the upper end of valve 60 stem 178 for a purpose which will hereinafter be more fully described.

Loosely journaled on shaft 181 is a sheave 65 wheel or the like 185, and pivotally carried by this sheave wheel is a pawl 186 adapted to engage in an enlarged notch 187 formed in the ratchet wheel 182. A spring 188 engages the pawl 186 to urge the same toward the periphery of the ratchet wheel 182.

The lever 130c is extended beyond its point 70 of pivotal mounting on the head 26c to provide an extension 190, and pivoted to this extension is a pawl 191 adapted to engage the ratchet teeth 192 on the ratchet wheel 182. A spring 193 secured to the pawl 191 holds the 75

same in a position to engage the ratchet teeth, as will be readily apparent.

Extending around the sheave wheel 185 is a chain or other flexible element having the depending ends 185 and 186. It will be understood that these ends extend to a point adjacent the boiler floor where they may be conveniently grasped by an operator. The depending end 196 of the flexible element passes through a guide 197 carried by the support 180, and this portion of the chain or flexible element has fixed thereon a collar 198 adapted to engage the guide 197 to limit movement of the flexible member in one direction.

With the structure above described it will be understood that when the blower element is not in use the valves 182^c and 177 will be closed. If now, it is desired to effect an actuation of the blower element, the end 196 of the flexible element is pulled downwardly, the sheave wheel 185 at this time rotating relative to the ratchet wheel 182 and cam 183. The sheave wheel 185 is rotated until the pawl 186 thereon engages in the enlarged notch 187 in the ratchet wheel 182.

The end 195 of the flexible element is then pulled, with the result that the sheave wheel will be rotated in the opposite direction, and the ratchet wheel will be caused to rotate with the sheave wheel by virtue of the connection together of these two elements by the pawl 186. This reverse rotation of the sheave wheel will be continued until the collar 198 engages lug 187, it being understood that during this movement of the ratchet wheel, the cam 183 will be rotated so as to engage the valve stem 178 and open valve 177.

Opening of valve 177 admits fluid under pressure to fluid motor 128^c, with the result that the blower element is rotatively driven. As the blower element is rotated, the lever 180^c is actuated to periodically open and close valve 182^c. This rocking of lever 180^c effects a movement of the ratchet wheel 182 and cam 183 by virtue of the engagement of pawl 181 with the teeth on the ratchet wheel. Thus during rotation of the blower element, the cam 183 will be rotated with a step by step movement until it passes out of engagement with the valve stem 178, thus permitting valve 177 to close.

The cam 183 is preferably rotatively adjustable with reference to the ratchet wheel 182, there being a set screw 199 associated with the hub of the cam to fix the cam in adjusted position. The arrangement is such that the cam may be set so that it will be moved out of engagement with the valve stem 178 after the blower element has completed one revolution. If it is desired that the blower element move through more than one revolution, the cam 183 may be so adjusted relative to the ratchet wheel that when the ratchet wheel has been moved to such an extent that the collar 198 engages lug 187, the cam will be in such a position that it will require two or more complete rotations of the blower element to move the cam out of engagement with the valve stem 178. Thus the cam may be readily adjusted so that after the operation of the blower element has been initiated, the blower element will continue to be operated through a desired plural number of rotations.

It will be apparent that cleaning fluid may, if desired, be at all times supplied to supply pipe 126^c, the arrangement being such that the blower element will not be operated until the flexible actuating chain or element has been manipu-

lated in the manner above described. The operation of the blower element is dependent upon a prior opening of valve 177, the opening of this valve initiating the movement of the blower element and the movement of the blower element controlling the flow of cleaning fluid to the same.

In Figs. 12 to 15, inclusive, there is disclosed electrically controlled means for accomplishing the results accomplished by the sheave 185, ratchet wheel 182, cam 183 and associated structure disclosed in Figs. 10 and 11. In the modified construction, the reference character 136^d designates a conduit similar to the conduit 136^c in that it extends to a fluid motor (not shown) which is arranged to drive a suitable blower element (also not shown). The valve 177^d controls the flow of fluid under pressure through this conduit, this valve being normally closed by a spring 179^d, which spring is sleeved on the stem 178^d of the valve.

The stem of the valve is arranged to be engaged by a cam 183^d, which cam is mounted on a shaft 181^d, there being also fixed to this shaft for rotation with the same a ratchet wheel 182^d. This ratchet wheel has teeth 192^d adapted to be engaged by a pawl 191^d pivotally carried by the extension 190^d of the valve actuating lever (not shown) of the blower head (not shown). It will be apparent that, as in the previously described form of construction, when the blower element is rotated, the pawl 191^d will be periodically actuated to ratchet the wheel 182^d about its axis and to thus move the cam 183^d with reference to the valve stem 178^d.

For the purpose of initially actuating cam 183^d to thus open valve 177^d, an electrically controlled mechanism is provided. This mechanism includes an electric motor 200 on the shaft of which is mounted a worm 201, this worm drivingly engaging a worm wheel 202 which is rotatably journaled on the shaft 181^d. The control means for the electric motor 200 is so arranged that each time the circuit is closed through the electric motor the worm wheel will be caused to rotate through one revolution, stopping in each instance in the position shown in Fig. 12 of the drawings.

The control means for the motor comprises the leads 205 and 206 which are suitably connected to any suitable source of current (not shown). Lead 206 is connected to a brush 207, this brush being also directly connected by lead 208 to one terminal 209 of the motor 200. The other terminal of the motor is connected by a lead 211 to one terminal 212 of a switch designated generally by the reference character 213. The other terminal 214 of this switch is directly connected by a lead 215 with the lead 205.

A switch arm 216 is provided for closing the circuit between terminals 212 and 214, the arrangement being such that when this circuit is closed, electrical energy is supplied to the motor 200 to cause rotation of this motor. The switch arm 216 is solenoid actuated, the arrangement being such that when this switch arm is initially, manually or otherwise actuated, it will be held in closed position until the electric motor has rotated sufficiently to rotate the worm wheel through 360°.

To accomplish this, there is provided a solenoid 217 connected to the switch arm 216 to actuate the same. One terminal of this solenoid is directly connected to the lead 205 by a lead 218, while the other terminal of this solenoid is con-

nected by lead 219 to brushes 220 and 221. These brushes are disposed on opposite sides of the brush 207, the three brushes being spaced apart and being arranged to engage a contact strip 222 mounted on the worm wheel 202 for rotation with the latter. It will be understood that whenever the solenoid 217 is energized, the switch 216 is closed, while whenever the solenoid is de-energized, the switch arm 216 is moved to the position shown in full lines in Fig. 12 of the drawings, by any suitable means (not shown).

In the operation of this control means, as thus far described, it will be understood that with the parts in the position shown in Fig. 12 of the drawings, no current will be supplied from the leads 205 and 206 to the motor 200. When, however, the switch arm 216 is moved into engagement with contact 214, current is supplied to the motor by way of leads 206 and 208 on the one hand and lead 211, switch 213 and leads 215 and 205 on the other hand. This will immediately start a rotation of the motor and thus a rotation of the worm wheel 202. As soon as the contact strip 222 moves sufficiently to span the space between brushes 220 and 207, a circuit will be completed through the solenoid 217 by way of lead 206, brush 207, contact strip 222, brush 220 and lead 219. This will effect an energization of the solenoid and will hold the switch arm 216 in engagement with contact 214, thus holding closed the circuit through the motor 200.

The solenoid will remain energized for a short period even after the rear end portion of contact strip 222 has passed out of engagement with brush 220, for during this interval, the circuit will be closed through the solenoid by way of lead 206, brush 207, contact strip 222, brush 221 and lead 219. As soon, however, as the end of strip 222 passes out of engagement with brush 207, the circuit through the solenoid will be broken, thus permitting switch arm 216 to move out of engagement with contact 214, and thus breaking the circuit through the motor 200.

The rotation of the worm wheel through an arc of 360° is utilized for the purpose of adjusting the position of cam 183^d with reference to the valve stem 178^d, it being understood that this cam opens valve 177^d and holds the same open until the cam is moved out of engagement with the end of the valve stem. This is accomplished by forming in the ratchet wheel 182 a circumferentially extending slot 225 and by loosely mounting a pin 226 in an opening 227 formed through the worm wheel 202. The pin 226 is so positioned from the center of the worm wheel as to register with the slot 225.

A spring 228 surrounds the pin 226 and engages a head 229 formed on this pin to normally urge the pin rearwardly so that the head thereof engages a cam member 230 which is supported adjacent the shaft 181^d for rotative adjustment with respect to the same. This cam is provided with the cutaway portion 231, this cutaway portion being of sufficient depth so that when rotation of the worm wheel brings the pin opposite this cutaway portion of the cam, the end of the pin will be withdrawn from engagement in the slot 225. The cam is also provided with an inclined portion 232 which connects the cutaway portion to the raised portion 233 of the cam, the arrangement being such that as the worm wheel is rotated, carrying with it the pin, the head of the pin rides up on the inclined portion 232 of the cam and is thus projected from the worm wheel and through the slot 225 in the ratchet wheel.

With the structure disclosed, it will be apparent that the amount of rotation imparted to the ratchet wheel 182^d and thus to the cam 183^d incident to rotation of the worm wheel 202 through 360° will be dependent upon the rotative positioning of the cam 230 with reference to the ratchet wheel. With the parts in their normal positions, it will be understood that the ratchet wheel 182^d will be in such a position that the slot 225 thereof will be substantially in the position shown by dotted lines in Fig. 12 of the drawings. At this time the cam 183^d will be out of engagement with the valve stem 178^d, and the valve 177^d will be closed.

If, now, the switch arm 216 is moved into engagement with contact 214, worm wheel 202 will be rotated through 360°. The initial rotation of the worm wheel will not, however, effect a rotation of the ratchet wheel, it being necessary first that the worm wheel rotate relative to the cam 20 sufficiently to bring the pin 226 out of registration with the cutaway portion of the cam to the end that the pin will be projected through the slot 225. The pin 226 will travel in the slot 225 until it reaches the end of the slot, at which time the ratchet wheel will be rotated with the worm wheel until the pin again comes opposite the cutaway portion of the cam. At this instant the pin will be withdrawn from the slot 225 by means of spring 228 so that the worm wheel may continue to rotate with reference to the ratchet wheel. Obviously, as the blower element (not shown) is driven, the pawl 191^d will be actuated periodically to ratchet the ratchet wheel 182^d in the direction in which it had previously been traveling. This movement of the ratchet wheel will eventually cause the cam 183^d to move out of engagement with stem 178^d, thus allowing a closing of valve 177^d. Since the rotation of the blower element and thus the actuation of pawl 191^d is dependent upon the fluid under pressure supplied to the blower head by way of conduit 186^d, it will be understood that as soon as the cam 183^d has been moved to a position where valve 177^d may close, the operation of the entire mechanism will be terminated.

It will be apparent that the extent of movement imparted to the ratchet wheel by the worm wheel will be dependent upon the rotative positioning of the cam 230 with reference to the ratchet wheel. Further, the amount of opening of the valve incident to any predetermined rotation of the ratchet wheel will be dependent upon the adjustable positioning of the cam 183^d with reference to the ratchet wheel. For this reason the cam 183^d and ratchet wheel 182^d are preferably secured to the shaft 181^d for adjustable rotative positioning with reference to the same. Likewise the cam 230, while not secured to the shaft 181^d, is suitably mounted on a support 235 so as to be adapted for adjustable rotative positioning with reference to the shaft 181^d.

It constitutes a feature of this form of construction to provide signals to indicate the interval during which the motor 200 is being operated and to indicate when the operation of the blower head to which the fluid under pressure is being supplied has been completed. To indicate the interval during which the motor is being driven, there is provided a lamp 236 which is connected to the leads 211 and 206. It will be apparent that when the leads 211 and 206 are energized and thus when electric current is being supplied to the motor 200, electric current will be supplied to lamp 236 to light the latter. Thus this lamp will

be lighted during the interval that the motor 200 is driven.

For the purpose of indicating the closing of valve 177^d and thus the completion of the operation of the blower head to which fluid under pressure is being supplied, there is provided a signal lamp 237 mounted in a lead 238 which terminates in a brush 239. This brush extends to adjacent the ratchet wheel 182^d and is disposed in spaced relation to a second brush 240 which is electrically connected to the lead 205 by a lead 241. The brushes 239 and 240 are spaced from the face of ratchet wheel 182^d, and formed on the face of the ratchet wheel is a relatively short contact strip 242 adapted to electrically connect the brushes 239 and 240 when the ratchet wheel has been rotated to a position where the cam 183^d is moved out of engagement with the valve stem 178^d.

It will be apparent that normally, when the system is not operated and the valve 177^d is closed, the lamp 237 will be illuminated. When, however, the ratchet wheel 182^d is rotated to a position where cam 183^d opens valve 177^d, the contact strip 242 will be moved out of engagement with brushes 239 and 240, thus breaking the circuit through lamp 237. This circuit will remain broken during the ratcheting of the wheel 182^d or until this wheel is moved to a position where closing of valve 177^d is permitted. Thus the lighting of lamp 237 will indicate that the blower element which the mechanism controls has operated the desired amount and the supply of fluid under pressure to the motor thereof has been cut off. It will be understood that while the signals have been described as comprising signal lamps, any other suitable signals may be substituted, either audible or visible.

With the blower elements controlled by mechanisms such as disclosed in Figs. 10 to 15, inclusive, it will be apparent that all of the blowers associated with any one boiler or with any group of boilers or fluid heaters might, if desired, be controlled from some central point either located adjacent the particular fluid heater being cleaned or located at some remote point such as the office or the like of the power plant. In Figs. 16 and 17 there is disclosed means whereby a plurality of control mechanisms of the character disclosed in Figs. 10 and 11 might, if desired, be located at some point adjacent the fluid heater with which the blower elements are associated.

Referring then particularly to these figures, the numeral 243 designates a fluid heater of any desired character such, for example, as a boiler. Associated with this fluid heater are the blower heads 26^e, it being understood that each blower head journals a suitable blower element (not shown), the blower elements extending into the fluid heater to discharge cleaning fluid adjacent the parts thereof to be cleaned. The heads 26^e may be of the character shown in Fig. 10, with the result that pendant from each blower head are the ends 195^e and 196^e of suitable flexible actuating elements. As brought out in the description of Fig. 10, suitable actuation of the depending ends of the flexible elements will cause operation of the blower heads with which the flexible elements are associated, the blower elements in each instance being operated for a predetermined period of time, dependent upon the setting of the particular heads.

The several flexible elements may be brought to adjacent the front of the fluid heater and the ends thereof engaged with sheave wheels 244

loosely mounted on a shaft 245. Each sheave wheel is preferably of a size substantially larger than the sheave wheel of the head which it controls, with the result that a slight rotation of the sheave wheels 244 will effect substantial rotative movements of the sheave wheels associated with the heads. Each sheave wheel 244 is also preferably provided with a handle 246 by which it may be rotated.

Disposed adjacent the sheave wheels 244 is 10 a main cleaning fluid supply conduit 247 to which it will be understood the several supply conduits for the blower elements are all connected. A valve 248 in the conduit 247 is preferably so located that it may be conveniently actuated by 15 the operator who is rotating the sheave wheels 244.

With this arrangement it will be apparent that an operator may cause the blower elements to operate in any desired sequence and either one 20 at a time or more than one at a time by first opening valve 248 and then by properly rotating the sheave wheels 244. It will be understood that these sheave wheels are rotatable entirely independently of each other with the result that the 25 blower elements may be operated in any order or sequence desired. Suitable indicating mechanisms may be associated with the blower elements to advise the operator of the fact that the blower elements are operating.

As disclosed in Fig. 18 of the drawings, a number of switches similar to the switch 213 shown in Fig. 12 of the drawings may be assembled at a central point to provide for the operation of a number of blower elements from this point. A 35 number of these switches, each being designated by the reference character 213^t are shown as being mounted on a suitable panel 250, it being understood that this panel may be located at any desired point, either adjacent to or remote from 40 the fluid heater or heaters to be cleaned.

As illustrated, each switch may comprise the spaced terminals 212^t and 214^t and a switch arm 216^t movable to electrically connect these spaced terminals. A push button 251 may be associated 45 with each switch arm for actuating the same, there being also associated with each switch arm a solenoid 217^t operating to hold its respective switch arm in contacting position until the motor which it controls has operated for the desired period of time. The signal lamps 236^t and 237^t will indicate the operation of the several 50 electric motors controlled by these switches and the several blower elements of the system.

As in the just previously described form of construction, the location of a plurality of controls at a central point permits a single operator to control the operation of a number of blower elements. Still further, the blower elements may be operated in any predetermined desired sequence 60 and if desired, two or more blower elements may be caused to operate during the same interval of time.

In Figs. 19 and 20 a further modified form of control mechanism is disclosed, this mechanism being adapted to provide for the operation of a blower element for a predetermined period of time. In these figures the numeral 136^b designates the conduit which supplies fluid under pressure to the fluid motor (not shown) of a 65 suitable blower head (also not shown). It will be understood that the fluid motor associated with the head may be adapted to either rotate or oscillate its respective blower element as desired.

the passage of fluid under pressure through the same is a valve 177^s, the stem 178^s of which is connected to a piston 260. This piston is mounted for reciprocation in a cylinder 261, this cylinder being in communication at its lower end with the interior of the conduit 136^s on the pressure side of the valve in this conduit. A spring 262 mounted between the piston 260 and the closed end of cylinder 261 provides means for closing the valve 177^s when fluid pressure has leaked past the piston so that pressures on opposite sides of the pistons are substantially equal.

It will be apparent that valve 177^s may be opened by venting the space between the piston 260 and the closed end of the cylinder, the pressure of the fluid in conduit 136^s then acting on the lower face of piston 260 to move the same upwardly against the force exerted by the spring 262. To vent this space, a conduit 263 is tapped into the cylinder 261, and this conduit may communicate either with the atmosphere or with any suitable exhaust. Disposed in conduit 263 is a valve 264, this valve being normally urged to its open position by a spring 265 which surrounds the stem 266 of the valve and engages a head 267 formed on this stem. A weight 268 normally engages the valve stem 266 to counteract the action of the spring 265 and to thus hold the valve 264 to its seat.

For actuating the weight 268 there is provided a solenoid 270, and this solenoid is supplied with energy by leads 271 and 272. The lead 272 is directly connected to a lead 273 which is connected at its one end to one terminal 274 of a double-pole switch 275 and which is connected at its other end to a synchronous constant speed motor 276. The other lead 271 is connected to a brush 277 for a purpose which will hereinafter be more fully described.

The double-pole switch 275 is provided for electrically connecting the terminals 278 and 274 to a power line 279. Connected to the terminal 278 is a lead 280 which is connected to a terminal 281 from which a lead 282 extends, this lead being connected to a brush 283 disposed adjacent the brush 277. A switch arm 284 is provided for electrically connecting terminal 281 to a terminal 285, this terminal being connected by a lead 286 to the motor 276 and by a second lead 287 to a brush 288 disposed adjacent the brushes 277 and 283. The three brushes are arranged to wipe a contact strip 290 carried by a drum 291 which is rotatively driven by the motor 276. It will be noted that the contact strip extends only partly around the drum 291 so as to provide that at one portion during the rotation of the drum the brushes will be free from contact with the strip.

In operation, the switch is closed and the contact arm 284 then actuated to connect terminals 281 and 285. At this instant electrical current will be supplied to the motor 276 by way of leads 280 and 286 on the one hand and by way of lead 273 on the other hand. This will cause a rotation of drum 291 and will bring the contact strip 290 of the drum into engagement with the brushes 277, 283, and 288. As soon as these brushes engage the contact strip, the switch arm 284 may be released, there being provided suitable means (not shown) for moving this switch arm out of engagement with terminal 285 at this time. The motor however, will continue to rotate until the brushes pass out of engagement with the contact strip 290, current at this time being supplied to the motor by way of leads 280 and 282, brush 283, contact strip 290, brush

288 and leads 287 and 286 on the one hand and lead 273 on the other hand. During this period of rotation of the motor, electrical energy will be also supplied to the solenoid 270 by way of leads 273 and 272 on the one hand and by way of leads 280, 282, brush 283, contact strip 290, brush 277 and lead 271 on the other hand. Thus the solenoid will be energized during the period that the brushes 277 and 283 are engaged by the contact strip 290.

Energization of the solenoid 270 raises the weight 268 out of engagement with the valve stem 266 whereupon the spring 265 opens valve 264, thus effecting a venting of the cylinder 261 above the piston therein. As soon as the cylinder is vented, the pressure acting on piston 260 opens valve 177^s and permits fluid under pressure to flow through conduit 136^s to the fluid motor which operates the blower element which is being controlled. Obviously, as soon as the contact strip 290 passes out of engagement with brushes 277 and 283, the solenoid 270 will be de-energized, thus allowing the weight 268 to again fall upon the valve stem 266, thus closing valve 264.

It will be apparent that by providing suitable reduction gearing between the motor 276 and the drum 291, the interval of time in which the solenoid will be energized may be regulated as desired. Thus by providing a desired speed of rotation of the drum 291, the period of time during which the blower element operates may be established. A lamp 292 may, if desired, be connected to the leads 271 and 272 to thus indicate the energization of the solenoid and thus the operation of the control system.

In Fig. 21 a slightly modified form of construction is disclosed which includes conduit 136^h which, it will be understood, supplies fluid under pressure to the driving motor of a blower element. The valve 177^h in this conduit controls the flow of fluid through the same and thus to the fluid motor.

Valve 177^h is provided with stem 178^h, to the upper end of which is secured a head 300. The spring 301 engaging this head tends to normally urge the valve to its open position. Opposing the action of spring 301 is a weight 302, and engagement of this weight with the head 300 is controlled by solenoid 270^h which is supplied with current by leads 271^h and 272^h. It will be understood that the flow of current through these leads may be controlled in the manner disclosed in Figs. 19 and 20.

With this construction, when the solenoid is de-energized, the weight bearing on the head 300 will force valve 177^h to its seat. Whenever, however, the solenoid is energized, the weight will be lifted from engagement with the head 300, thus permitting spring 301 to open the valve.

In Figs. 22 and 23 a further modified form of construction is disclosed which includes conduit 136^k and valve 177^k disposed in this conduit for controlling the flow of pressure fluid through the same. In this instance the stem 178^k of this valve is secured to a piston 305 mounted for reciprocation in a cylinder 306. Formed within the cylinder is a partition 307 which provides a chamber 308 above the chamber 309 in which the piston reciprocates.

Tapped into the cylinder 306 below the piston therein is a conduit 310, and tapped into the conduit 136^k in advance of the valve therein is a conduit 311. The conduits 310 and 311 lead to a three-way valve 312, there being also a discharge conduit 313 for this valve. The valve

312 is provided with an actuating handle 314 which is disposed in the path of movement of the collar 315 fixed to the valve stem 178^k.

Formed in the partition 307 is a check valve 316 arranged to permit passage of fluid from chamber 308 to chamber 309, but preventing the return flow of fluid between these two chambers. A by-pass conduit 317 is provided, however, placing these two chambers in communication with each other, there being a needle valve 318 in this by-pass conduit for restricting the flow of fluid through the same.

In operation, when the actuating handle 314 is moved downwardly to the position indicated in dotted lines, pressure fluid is admitted from conduit 136^k to the cylinder 306 below the piston in this cylinder. This forces the piston 305 upwardly against the force exerted on the same by the spring 320, thus opening valve 177^k. Upward movement of the valve stem causes the collar 315 thereon to move the valve handle 314 to the position shown in solid lines, in which position the conduit 310 is placed in communication with the exhaust conduit 313.

25 As soon as the pressure fluid is exhausted below piston 305, spring 320 acts to return the piston to its original position and thus acts to close valve 177^k. This movement of the piston is retarded by the restricted passage of fluid from chamber 308 to the chamber 309 above the piston. Thus by properly adjusting needle valve 318, the closing of valve 177^k may be retarded to a desired extent.

It will be understood that as long as valve 177^k is open, fluid under pressure will be supplied to the blower element actuating motor so that the blower element will be operated. The retarded closing of the valve 177^k thus provides for the operation of the controlled blower element for a predetermined period of time.

In Figs. 24 to 26, inclusive, a further modified form of construction is disclosed which, however, is quite similar to that disclosed in Figs. 22 and 23. In this modified form of construction there is provided conduit 136^m in which is mounted valve 177^m. This valve is provided with stem 178^m which is secured to piston 305^m. A collar 315^m on the valve stem is arranged to actuate lever 314^m which controls valve 312^m, this valve controlling communication between conduit 310^m and supply and exhaust conduits 311^m and 313^m respectively.

55 In this modified form of construction, the valve stem 178^m is extended through the piston, and engaging the upper end thereof is a lever 320. This lever may itself be relatively heavy or may be weighted so that its engagement with the valve stem tends to move the valve 177^m to its closed position.

60 The lever 120 is pivotally mounted at its one end on a shaft 321, and disposed on this shaft is a ratchet wheel 322, the teeth of which are engaged by a pawl 323 pivotally mounted on lever 320. An escapement mechanism is provided for retarding rotative movement of the ratchet wheel 322 in one direction, this escapement mechanism including ratchet wheel 324 and pendulum 325 having dogs 326 formed on the end thereof for engagement with the teeth on ratchet wheel 324. A weight 327 is mounted on the pendulum for adjustment longitudinally thereof to thus provide for varying the swing of the pendulum.

75 It will be understood that in operation, if the valve actuating lever 314^m is moved downward-

ly, fluid under pressure will be admitted to cylinder 306^m below the piston therein, thus forcing this piston upwardly and opening valve 177^m. This upward movement of the piston and valve will actuate valve 312^m to connect conduit 310^m to the exhaust. During the upward movement of the valve 177^m the pawl 323 will idle over the teeth of ratchet wheel 322, but as soon as the space below piston 305^m is connected to the exhaust, the weighted arm or lever 320 acting 10 on the stem of valve 177^m will tend to return this valve to its closed position. The movement of lever 320 incident to closing of the valve will be retarded by the escapement mechanism, with the result that by properly adjusting the escapement mechanism, the valve 177^m may be held open for a desired period of time. 15

From the above it will be apparent that the invention provides control means for blower elements whereby the blower elements may be caused 20 to operate for desired periods of time or through desired numbers of revolutions. In each instance the operation of the blower element may be initiated by a means which may be remote from the blower element and the operation of the 25 blower will be automatically terminated without further action on the part of the operator.

While several embodiments of the invention have been disclosed, it is to be understood that the right is reserved to make such changes in 30 the details of construction and arrangement of parts as will fall within the purview of the attached claims.

What we claim as our invention is:

1. In a fluid heater cleaner, a movable blower 35 element, a source of supply of cleaning fluid under pressure, a fluid motor for moving said blower element, means operating to admit cleaning fluid to the blower element during a portion of its movement, means for admitting cleaning fluid under pressure directly from said source to said fluid motor to actuate the latter, and means operating after cleaning fluid is admitted to the blower element to conduct cleaning fluid from the blower element to the fluid motor to actuate the 40 latter and to cut off the direct supply of cleaning fluid from said source to said fluid motor.

2. In a fluid heater cleaner, a rotatable blower element, a source of supply of cleaning fluid under pressure, a valve for controlling the admission 50 of cleaning fluid from said source to said blower element, means operating to open said valve during a portion only of the rotation of the blower element, a fluid motor for rotating the blower element, a second valve connected on the supply 55 side of said first valve and to said fluid motor for controlling the flow of cleaning fluid from said source of supply to said fluid motor, means for opening said second valve and holding it open until said first valve has been actuated, and means communicating with said blower on the blower element side of said first valve for conducting cleaning fluid under pressure from said blower element to said fluid motor for continuing the actuation of the latter after closing of 60 said second valve, said second valve being so constructed and arranged as to be closed by the pressure of the cleaning fluid when the cleaning fluid is conducted from the blower element to the fluid motor.

3. In a fluid heater cleaner, a rotatable blower element, means operating in timed relation to the rotation of the blower element to admit cleaning fluid to the same, a fluid motor for rotating the blower element, means for supplying 70

fluid under pressure to said fluid motor to start the actuation thereof prior to the admission of cleaning fluid to the blower element, and means operating upon the admission of cleaning fluid to the blower element to conduct cleaning fluid from the blower element to the fluid motor to actuate the latter and to cut off the initial supply of fluid under pressure to the fluid motor.

4. In a fluid heater cleaner, a rotatable blower element, a fluid motor for rotating said blower element, a valve for controlling the admission of cleaning fluid to the blower element, means operating to periodically open and close said valve upon rotation of the blower element, means for admitting fluid under pressure to said fluid motor to actuate the latter, and means separate from but controlled by the actuation of said valve for cutting off the supply of fluid under pressure to said fluid motor after a predetermined plural number of rotative movements of the blower element.

5. In a fluid heater cleaner, a rotatable blower element, a fluid motor for rotating said blower element, a source of supply of cleaning fluid under pressure, a valve controlling the admission of cleaning fluid from said source of supply to said blower element, means for periodically opening and closing said valve upon rotation of the blower element, a second valve for admitting cleaning fluid under pressure from said source to said fluid motor to actuate the latter, means for conducting cleaning fluid under pressure from said blower element to said fluid motor to actuate the latter during the periods that cleaning fluid is being supplied to the blower element, and means for holding said second mentioned valve open during a plural number of rotative movements of said blower element, said means providing for a closing of said second mentioned valve after a predetermined plural number of rotative movements of the blower element.

6. In a fluid heater cleaner, a rotatable blower element, a valve controlling the admission of cleaning fluid to the blower element, means for periodically actuating said valve upon rotation of the blower element, a fluid motor for rotating the blower element, a valve for admitting fluid under pressure to said fluid motor to actuate the latter, a holding means for retaining said second mentioned valve in open position, and means actuated in timed relation to the operation of said first mentioned valve for releasing said holding means after a predetermined plural number of rotative movements of said blower element.

7. In a fluid heater cleaner, a rotatable blower element, a fluid motor for rotating said blower element, a valve for controlling the admission of fluid under pressure to said fluid motor, means for opening said valve and for holding the same open, and means operating in timed relation to the rotation of the blower element to actuate said valve opening and holding means to provide for a closing of said valve after a predetermined plural number of rotative movements of the blower element, each rotative movement of the blower element including movement thereof away from and substantially back to its initial position.

8. In a fluid heater cleaner, a rotatable blower element, a fluid motor for rotating said blower element, a valve controlling the admission of fluid under pressure to said fluid motor, means including a cam for opening said valve and for holding the same open, and means operating upon rotation of said blower element to move said cam to provide for a closing of said valve

after a predetermined rotation of said blower element through an arc greater than 360 degrees.

9. In a fluid heater cleaner, a rotatable blower element, power driven means for rotating said blower element, a cam controlling the supply of power to said power driven means, means for moving said cam to a position where power is supplied to said power driven means, and means operating upon rotation of said blower element through more than 360 degrees to provide for movement of said cam to a position where the supply of power to said power driven means is cut off.

10. In a fluid heater cleaner, a movable blower element, a motor for moving said blower element, means operating in timed relation to the operation of the motor for admitting cleaning fluid to the blower element, a single means operating when given a single power impulse to start the operation of the motor to thus initiate the operation of the blower element, and means for terminating the operation of the motor after the blower element has been moved away from and returned to its initial position a predetermined plural number of times.

11. In a fluid heater cleaner, a movable blower element, a motor for moving said blower element, means operating in timed relation to the operation of the motor for admitting cleaning fluid to the blower element, a single actuating member operating when given a single power impulse to start the operation of said motor to thus initiate the movement of the blower element, and means operating after the blower element has been moved away from and returned to its initial position a predetermined plural number of times to terminate the actuation of the motor and to cut off the supply of cleaning fluid to the blower element.

12. In a fluid heater cleaner, a movable blower element, a motor connected to said blower element for moving the same, means operating in timed relation to the operation of said motor for admitting cleaning fluid to the blower element, a flexible actuating member, means operating upon the application of a single pull to said actuating member to start the operation of said motor to thus initiate the movement of the blower element, and means operating after a predetermined plural number of rotative movements of the blower element through 360 degrees to return said actuating member to its original position to terminate the operation of said motor and to cut off the supply of cleaning fluid to the blower element.

13. In a fluid heater cleaner, a movable blower element, a fluid motor for moving said blower element, a valve controlling the flow of fluid under pressure to said fluid motor, means including a movable member for opening said valve and for holding the same open, and means operating upon movement of said blower element to move said movable member to provide for a closing of said valve after said blower element has been moved away from and returned to its initial position a predetermined plural number of times.

14. In a fluid heater cleaner, a rotatable blower element, a cleaning fluid supply line for said blower element, a valve in said supply line, means operating to open said valve during a portion of the rotation of the blower element, a fluid pressure actuated motor connected to said blower element for rotating the same, a conduit for supplying fluid under pressure to said fluid motor, a valve in said conduit, means for opening said

- valve, and means actuated by the pressure of the cleaning fluid supplied to the blower element upon opening of the valve in the cleaning fluid supply line for holding said second mentioned 5 valve open whereby fluid under pressure is supplied to said motor whenever cleaning fluid is supplied to said blower element.
15. In a fluid heater cleaner, a movable blower element, power driven means for moving said blower element through a plurality of cycles of movement, each cycle including a movement of the blower element away from and substantially back to an initial starting point, means controlling the supply of power to said power driven 10 means, and means operating after said control means has been actuated to supply power to the power driven means to prevent the cutting off of the supply of power to the power driven means until the blower element has been moved through 15 a predetermined plural number of cycles of movement.
16. In a fluid heater cleaner, a movable blower element, a source of supply of cleaning fluid, a valve controlling the flow of cleaning fluid to 20 the blower element, means for actuating said valve in timed relation to the movement of the blower element, power driven means for moving the blower element through a plurality of cycles of movement, means controlling the supply of power to the power driven means, means operating after said control means has been actuated to supply power to the power driven means to prevent the cutting off of the supply of power to the power driven means until the blower element 25 has been moved through a predetermined plural number of cycles of movement, and means actuated by said valve and operating upon the completion of the movement of the blower element through said predetermined plural number of 30 cycles of movement to provide for the cutting off of the supply of power to the power driven means.
17. In a fluid heater cleaner, a movable blower element, a fluid motor connected to said element for moving the same through a plurality of cycles 35 of movement, each cycle including movement of the blower element away from and substantially back to an initial starting position, a source of supply of fluid under pressure, a valve controlling the flow of fluid from said source to said fluid 40 motor, and means operating when said valve is opened to prevent closing of the valve until the blower element has been moved through a predetermined plural number of cycles, said last mentioned means then providing for a closing of 45 said valve.
18. In a fluid heater cleaner, a movable blower element, a fluid motor connected to said blower element for moving the same through a plurality of cycles of movement, each cycle including 50 movement of the blower element away from and substantially back to an initial starting position, a source of supply of fluid under pressure, a valve controlling the flow of fluid under pressure from said source to the motor, means for holding said 55 valve open, and means controlled by movement of the blower element for closing said valve after the blower element has been moved through a predetermined plural number of cycles of movement.
- 70 19. In a fluid heater cleaner, a rotatable blower element, a fluid motor connected to said blower element for rotating the same, a source of supply of fluid under pressure, a valve for control- 60 ling the flow of fluid under pressure from said source to said fluid motor, means for opening said valve, means to hold said valve open, and means operating to move said last mentioned means to provide for closing of the valve after a predetermined plural number of rotative movements of the blower element through 360 degrees. 5
20. In a fluid heater cleaner, a rotatable blower element, a source of cleaning fluid under pressure, a valve controlling the flow of cleaning fluid 10 from said source to the blower element, means for actuating said valve in timed relation to the rotation of the blower element, a fluid motor connected to the blower element for rotating the same, a second valve controlling the flow of cleaning 15 fluid to said fluid motor, means for opening said second valve, means for holding said second valve open, and means actuated by said first mentioned valve upon actuation thereof to move said holding means to provide for closing of said second mentioned valve after a predetermined plural number of rotative movements of the blower element. 20
21. In a fluid heater cleaner, a movable blower element, a source of supply of cleaning fluid under pressure, means controlling the flow of 25 cleaning fluid to the blower element, a fluid motor connected to the blower element for moving the same, a valve member operable in one position to admit cleaning fluid from said source to the motor and operable in a second position to admit 30 cleaning fluid from said element to the motor and to cut off the direct supply of cleaning fluid from the source to the motor, and means for actuating said valve member.
22. In a fluid heater cleaner, a movable blower 35 element, a source of supply of cleaning fluid under pressure, means controlling the flow of cleaning fluid to the blower element, a fluid motor connected to the blower element for moving the same, a valve member operable to control communication between the source of supply of 40 cleaning fluid and the motor and between the blower element and the motor, means for moving said valve to place said fluid motor in communication with the source of supply of 45 cleaning fluid, and means providing for movement of said valve to a position where it places the blower element in communication with the fluid motor upon the admission of cleaning fluid to the blower element. 50
23. In a fluid heater cleaner, a rotatable blower element, a source of supply of cleaning fluid, a valve controlling the flow of cleaning fluid from 55 said source to the blower element, means for actuating said valve in timed relation to the rotation of the blower element, a fluid motor connected to the blower element for rotating the same, a valve controlling the admission of fluid under pressure to the fluid motor, means normally acting to close said valve, a member movable to a position where it opens said valve and holds the same open, a second member for holding said last mentioned member in the position where it holds the valve open, and means connected to the cleaning fluid control valve and 60 actuated thereby for moving the second member to a position where it releases said first member to permit closing of the valve. 65
